PAPER MAKING APPARATUS

Benjamin E. Teale, Lee, Mass.

Application July 5, 1932. Serial No. 620,817

15 Claims. (Cl. 92—44)

This invention relates to improvements in paper making apparatus and is directed more particularly to an adjustable slice structure for use in connection with the Fourdrinier wire and frame of a paper machine.

The principal objects of the invention are directed to the provision of a slice device having an adjustable edge and which is made as a unitary structure so that it may be readily and easily attached to and removed from a paper making machine.

According to special features of the invention the unitary slice device includes a novel supporting member which may be supported by a paper making machine and is removable therefrom while a lower edge portion of a part thereof is adjustable so that it may be deformed or adjusted relative to the transverse contour of a Fourdrinier wire. This functions to insure the desired distribution of paper making material on the Fourdrinier wire and in that way facilitates the production of a web having a substantially uniform thickness transversely thereof.

Various novel features and advantages of the invention will be more fully hereinafter referred to in connection with the accompanying description of the preferred form thereof with reference being had to the accompanying drawings, wherein:

Fig. 1 is a longitudinal diagrammatic sectional view showing a paper making apparatus having the slice device of the invention associated therewith.

Fig. 2 is a transverse sectional view at a larger scale through the slice device of the invention.

Fig. 3 is a front elevational view of the slice device shown in Fig. 2.

Fig. 4 is an end elevational view of the device shown in Fig. 3.

Fig. 5 is a diagrammatic representation of the lower edge of the slice as it is formed or distorted so as to approximate the contour transversely of a Fourdrinier wire.

Fig. 6 is a view similar to Fig. 2 showing a modified form of the invention.

Fig. 7 is a partial elevational view of a slice plate of the structure shown in Figs. 6 and 8, and

Fig. 8 is a view similar to Fig. 3 showing a modified form of the invention.

Referring to the drawings more in detail the invention will now be fully described.

In Fig. 1 there is diagrammatically shown so much of a paper making apparatus as will explain the novel features and mode of operation of the device of the invention. 2 is a flow-box

for paper making material and 3 is an apron at one side thereof over which paper making material flows onto a Fourdrinier wire 4. The wire 4 is carried in the usual way at one end of the machine by a breast roll 6 and its opposite end by a couch roll 8 and a plurality of table or supporting rolls 10 underlie and support the upper run of the Fourdrinier belt while the usual stretch rolls 12 are shown in engagement with the lower run of the wire.

Deckle straps 18 are associated with the wire 4 at either side of the machine and are supported by pulleys 14 so that the lower runs of the straps may rest on the Fourdrinier wire at opposite sides thereof in the usual way.

A slice 20 is located adjacent the ends of the deckle straps and a dandy roll 22 is disposed at the opposite end of the machine above the Fourdrinier wire. Suction boxes 24 of usual form are located therebelow.

In the normal operation of the paper making machine the paper making material flows from the box 2 across the apron 3 and onto the Fourdrinier wire, while the slice 20 functions to level off the material as the wire carries the material past the lower edge thereof. The slice 20 is not adapted to insure an even layer of paper making material on the wire in the event the wire is uneven or not flat transversely. The wire transversely may be more or less uneven, that is, it may have relatively high and low spots so that the material varies in thickness and is therefore not of uniform thickness transversely of the wire as the material may be of relatively varying thickness as between the central and side portions of the wire. It is to overcome these difficulties and produce a web of paper having substantially uniform thickness that the novel features of the invention are directed. At the same time the means therefore is constructed as a unit so as to be removable from and attached to the machine when desired and is readily adjustable for its function as will appear.

The novel features of the slice device of the invention indicated generally by D will now be described. A support preferably in the form of an angle, as shown, is provided which may extend across the machine. This has a leg 30 and a leg 32 in angular diverging relation with respect thereto the former of which is preferably disposed in an angular relation relative to the plane of the Fourdrinier wire. The support is made in the form shown so as to be rigid and relatively non-bendable and has secured on its outer end brackets 36 which are formed with vertically extending

plate portions 38 as shown in Fig. 4. Other plates 39 may be secured to the frames of the machine to receive therebetween the plates of the brackets and thereby hold the support in the desired manner.

Adjusting screws 40 are threaded in the brackets 36 and are arranged to rest on the frame 16 at either side of the machine. By adjusting the screws 40 the slice unit may be moved up and down.

A slice member 44 has an upper end fastened to a member 46 by means of bolts 48 while the member 46 is secured to the leg 32 of the support by means of bolts 50. The slice 44 is preferably of relatively thin and more or less spring-like metal so that its relatively free body portion and lower edge may be bent or distorted while its upper end is fixed rigidly to the rigid support.

A plurality of adjusting bolts 52 and in spaced relation longitudinally of the support, as shown, have their lower ends connected to the slice 44 at some distance upwardly from the lower working edge 45 thereof. Flanges such as 53 may be secured to the slice 44 and in which the bolts 52 are pinned and have been found to be suitable for connecting the bolts to the slice.

Adjusting members 54 are rotatable in the leg 30 of the support and are held against longitudinal shifting movements by collars 55 in threaded engagement therewith at the under side of the leg 30. The upper ends 56 of the rods 52 are threaded as shown so that by means of the members 54, the rods 52 are moved relative to the support. Locking members 58 also in threaded engagement 35 with the rods 52 are provided for binding against the members 50 so as to lock the rods in adjusted positions.

Stiffening plates 53' are associated with the legs 30 and 32 of the support and in the preferred form of the invention are located at opposite ends thereof and in spaced relation therealong. These may be secured to the legs of the support in any suitable manner and are arranged to give to the support rigidity and strength whereby the support 45 in the operation of the apparatus will not bend or flex to any appreciable extent.

The device is adapted to be associated with a Fourdrinier wire and in the operation of the apparatus the Fourdrinier wire carries the paper making material forwardly beneath the plate 44 of the device. The paper making material may change between what is known as "free stuff" and "slow stuff" during the operation of the machine. In such an event the material is likely to be of a different thickness at the central part of the wire as compared with the side parts. The amount of shake of the wire, the speed of shake with respect to the speed of the wire also may tend to bring about an uneven layer of stuff on the wire. As has been stated in some cases the Fourdrinier wire may not be flat transversely, that is it may have relatively high spots and low spots forming an uneven contour.

With the support in place as shown the lower edge 45 of the slice plate 44 may be moved at intervals by the adjusting bolts towards and away from the Fourdrinier wire or be distorted along its lower edge so as to approximate the contour of the wire, the edge being represented by 45 in Fig. 5. In this way since the edge of the slice may be made to conform to the transverse contour of the wire and overcome the difficulties above mentioned.

As will be seen the support is constructed in

such a way as to be rigid while the slice plate is attached at one end thereto with the adjusting members disposed at substantially right angles thereto to bring about the most accurate and positive adjustment of the lower edge of the slice plate. By providing the rigid support the likelihood of bending is obviated which would effect the adjustment of the lower edge of the plate relative to the wire and by providing a unitary structure the device may be moved from and placed in the paper machine at will.

The form of the invention shown in Figs. 6, 7 and 8 will now be described.

In this case a support 60 is provided which may be tubular so as to be rigid and its ends are preferably pivoted for adjustment in some suitable manner as in frames 62 as shown. Flanges 64 may carry the ends of the support and have clamping means such as clamp collars 66 associated therewith so the support may be held in various positions of angular adjustment.

A plurality of brackets 68 are carried by the support and are adjustable longitudinally thereof being split to provide separate lugs 70. Bolts 72 extend through the lugs and nuts 73 on the ends 100 in threaded engagement therewith function to draw the lugs together whereby the brackets may be clamped to the support in various positions of adjustment. The brackets are preferably held against rotation on the support by the key and slot 105 connection shown, 74 representing a key in each bracket slidable in a groove 76 of the support.

A slice plate 80 which is preferably of relatively thin flexible material such as sheet metal is provided which has entrance slots 82 and longitudinal anchoring slots 84 along its upper edge.

With the nuts 73 loosened the plate may be manipulated so the bolts 72 of the brackets are passed through the slots 82 and then by moving the plate longitudinally the bolts are received in the slots 84. In this way the plate is readily removed and attached to the brackets and clamped in place thereon, facilitating the changing of one plate to another. By changing the relative position of the brackets it is possible to adapt the apparatus for machines of various widths.

Adjusting screws 90, adjusting and check members 92 and 94 respectively are associated with ears 71 of the brackets and function similarly to the structure shown in Fig. 2.

Guides 96 are associated with the lower portion of the plate 80 and are provided with grooves or slots 98, as shown, over the sides of which extend lips 100. Flanges or heads 102 are carried by the members 90 which are receivable in the grooves of the members 96 as the plate 80 is moved longitudinally of the brackets and in this way the lower edge of the plate 80 is detachably attached to or disconnected from the adjusting members 130 while its upper edge is connected to or disconnected from the brackets.

In this form of the invention the support may be turned on its axis to raise and lower the lower edge of the plate 80 while the lower edge may be 140 adjusted by means of the members 90. Altogether it is possible to obtain the utmost precision of adjustment and thereby effect the desired accuracy in results. This form of the apparatus may function in the manner already described and need not be more fully described at this time.

Having described the invention, what it is desired to claim and secure by Letters Patent of the United States is:

1. The combination of the Fourdrinier wire and side frames of a paper machine with a unitary slice device comprising, a support for resting on said frames having diverging leg portions, a flexible slice member attached to the end of one of said leg portions having a free end extending in a substantially parallel relation with respect to the other leg portion and a plurality of adjusting devices associated with the free end of the slice member and end of said other leg portion to move the free end of the slice member towards and away from said other leg portion.
2. The combination of the Fourdrinier wire and side frames of a paper machine with a unitary slice device comprising, a support for resting on said frames having diverging leg portions, a flexible slice member attached to the end of one of said leg portions having a free end extending in a substantially parallel relation with respect to the other leg portion, a plurality of adjusting devices associated with the free end of the slice member and end of the said other leg portion to move the free end of the slice member towards and away from said other leg portion, and reinforcing members at spaced intervals along said support extending between and secured to said leg portions.
3. The combination of the Fourdrinier wire and side frames of a paper machine with a unitary slice device comprising, a support having diverging leg portions, brackets at opposite ends of the support including means for resting on said frames to position the support over the wire, a flexible slice member having a longitudinal edge secured to a longitudinal edge of one of said leg portions providing a substantially free body portion and a longitudinal working edge, a plurality of rotatable members in spaced relation along the longitudinal edge of the other leg portion and a plurality of screws attached to the slice member adjacent the working edge thereof and in threaded engagement with said rotatable members whereby the edge of the slice member may be deformed to align with the contour of the Fourdrinier wire.
4. The combination of the Fourdrinier wire and side frames of a paper machine with a unitary slice device comprising, a support having diverging leg portions, brackets at opposite ends of the support having means for resting on said frames, a flexible slice member having a longitudinal edge secured to a longitudinal edge of one of said leg portions providing a substantially free body portion and longitudinal working edge, a plurality of rotatable members in spaced relation along the longitudinal edge of the other leg portion and a plurality of screws attached to the slice member adjacent the working edge thereof and in threaded engagement with said rotatable members whereby the edge of the slice member may be deformed to align with the contour of the Fourdrinier wire.
5. The combination of the Fourdrinier wire and side frames of a paper machine with a unitary slice device comprising, a support having diverging leg portions, brackets at opposite ends of the support having means for resting on said frames, a flexible slice member having a longitudinal edge secured to a longitudinal edge of one of said leg portions providing a substantially free body portion and longitudinal working edge, a plurality of rotatable members in spaced relation along the longitudinal edge of the other leg portion and a plurality of screws attached to the slice member adjacent the working edge thereof and in threaded engagement with said rotatable members whereby the edge of the slice member may be deformed to align with the contour of the Fourdrinier wire.
6. The combination of the Fourdrinier wire and side frames of a paper machine with a unitary slice device comprising, a support having diverging leg portions, brackets at opposite ends of the support having means for resting on said frames, a flexible slice member having a longitudinal edge secured to a longitudinal edge of one of said leg portions providing a substantially free body portion and longitudinal working edge, a plurality of rotatable members in spaced relation along the longitudinal edge of the other leg portion and a plurality of screws attached to the slice member adjacent the working edge thereof and in threaded engagement with said rotatable members whereby the edge of the slice member may be deformed to align with the contour of the Fourdrinier wire.
7. A unitary slice device comprising in combination, a support, a plurality of brackets thereon, a slice plate and detachable connections to said brackets along one side edge, adjusting means associated with the said brackets and detachable connections between the same and the other side edge of said plate, the said brackets being slidable along said support and provided with means to clamp the same to the support in various positions of adjustment.
8. A unitary slice device comprising in combination, a support, a plurality of brackets thereon, a slice plate and detachable connections to said brackets along one side edge, adjusting means associated with the said brackets and detachable connections between the same and the other side edge of said plate, the said brackets being slidable along and non-rotatable relative to said support and provided with means to clamp the same to the support in various positions of adjustment.
9. A slice device comprising in combination, a support, a plurality of brackets slidable but non-rotatable on said support and means to clamp the brackets thereto, adjusting screws associated with said brackets, a flexible slice plate having slots to receive said clamping means and detachable connections for said screws whereby said plate may be detachably secured to said brackets, the said detachable connections including grooved members on the plate receiving enlarged portions on the screws.
10. The combination with a supporting structure with an adjustable slice device comprising, a support journaled in said supporting structure, means to clamp the support in various positions of angular adjustment, brackets adjustable along said support, a slice plate connected at one edge

to said brackets and adjustable connections between the other edge of said blade and brackets, the said connections between said plate and brackets being adapted to permit the plate to be 5 detached from the brackets.

11. The combination of the wire and side frames of a paper machine with a unitary slice device comprising, a support for resting on said frames having diverging leg portions, a flexible slice member having a longitudinal side edge portion secured to the end of one leg portion having a free end extending therefrom in spaced relation with respect to the end of the other leg portion and a plurality of adjusting devices associated with the free end of the slice member and end of said other leg portion of the support to move the free end of the slice member towards and away from said other leg portion.

12. The combination of the wire and side frames of a paper machine with a unitary slice device comprising, a support for resting on said frames having diverging leg portions, a flexible slice member having a longitudinal side edge portion secured to the end of one leg portion having a free end extending therefrom in spaced relation with respect to the end of the other leg portion, a plurality of adjusting devices associated with the free end of the slice member and end of said other leg portion of the support to move the free end of the slice member towards and away from said other leg portion and stiffening members in spaced relation associated with the leg portions of the support.

13. A unitary slice device comprising in com-
35

bination, a supporting member, a plurality of brackets thereon, a flexible slice plate connected at its opposite longitudinal sides to opposite sides of said brackets whereby it is supported entirely by the supporting member, the connections at one side of the plate and brackets being arranged to move the said edge towards and away from the brackets.

14. A unitary slice device comprising in combination, a supporting member, a plurality of brackets thereon, a flexible slice plate connected at its opposite longitudinal sides to opposite sides of said brackets whereby it is supported entirely by the supporting member, the connections at one side of the plate and brackets being arranged to move the said edge towards and away from said brackets, the connections at the sides of said plate and brackets including disengageable parts whereby the plate may be removed from the brackets.

15. A unitary slice device comprising in combination, a supporting member, a plurality of split brackets slidable along the supporting member, clamping means associated with said brackets to secure the brackets to the support, adjusting screws associated with said brackets, a flexible slice plate having one marginal edge secured to said clamping means of the brackets and engageable connections associated with said adjusting screws and the other marginal edge of the plate whereby the plate may be connected to and disconnected from the brackets.
